(57) **CLAIM**

We claim the ornamental design for a monitor, as shown and described.

DESCRIPTION

FIG. 1 is a front perspective view of a monitor showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion in FIG. 2;

FIG. 12 is an enlarged view of the encircled portion 12 in FIG. 3;

FIG. 13 is an enlarged view of the encircled portion 13 in FIG. 3;

FIG. 14 is an enlarged view of the encircled portion in FIG. 4;

FIG. 15 is an enlarged view of the encircled portion in FIG. 5;

FIG. 16 is an enlarged view of the encircled portion 16 in FIG. 6;

(Continued)

FIG. 17 is an enlarged view of the encircled portion 17 in FIG. 6;

FIG. 18 is an enlarged view of the encircled portion in FIG. 8;

FIG. 19 is another front view thereof showing the display screen of the monitor rotated in an alternate position; and, FIG. 20 is an enlarged view of the encircled portion in FIG. 19.

Dot-dash broken lines represent the boundaries of the enlarged portions and form no part of the claimed design. All other broken lines seen in the drawings depict portions of the monitor that form no part of the claimed design.
